WINDOW CONTROL

Lee W. Kent, Evanston, Ill.

Application August 31, 1942, Serial No. 456,762

4 Claims. (Cl. 292—76)

The present invention pertains, in general, to window sash controls of simple, inexpensive and efficient construction, preferably of a unitary or one-piece type adapted to lockingly engage and be carried by window sashes in coacting engagement with the upright members of a window frame to retain the window sashes in set positions of adjustment and to hold the sashes against rattling.

The present invention furthermore obviates the need of window weights, ropes, chains, pulleys, and window frame box construction, and affords simplified inexpensive holders which may be secured against the inner faces of the window sashes and in contact with the sash guide strips or, if preferred, the holders may be engaged against the side surfaces of the window sashes to ride in the sash guide grooves in slidable and spring contact with the window frame stiles.

It is an object of this invention to provide a simplified and inexpensive one-piece window sash holder constructed to have one end thereof lockingly engaged and secured to a window sash and including a curved portion or spring body adapted to be compressed when the holder is engaged to the sash and furthermore adapted to have resilient sliding contact with an upright member of a window frame in which the sash is slidably engaged, to hold the sash in selected positions in the window frame and braced to obviate rattling of the sash.

It is also an object of this invention to provide a simple unitary type of metallic window sash holder including a spring body portion having one end thereof formed with a projection extending at right angles to a tangent of the curvature of the spring body and adapted to be engaged into a slot or opening in the sash when the spring body is compressed and furthermore adapted to lockingly snap into said opening when the pressure on the spring body is released.

Another object of the invention is to provide an improved and simplified type of window sash holder consisting of a continuously curved metallic body strip having one end thereof bent over at right angles to a tangent to the curvature of the body portion to permit the bent end to be inserted into a slot in a window sash when the spring body portion is compressed and to snap into locking engagement between opposed surfaces forming the sash slot when the spring body portion of the holder is released to thereby securely lock one end of the holder to the sash while the opposite end is free to move with the compression of the spring body portion of the holder occasioned by the movement of the sash in a window frame.

It is a further object of this invention to provide an improved type of anti-rattling sash holder comprising a continuously curved spring

body strip having a toothed or serrated flange integrally formed at right angles to one end of the body strip and adapted to be driven into a window sash when the body strip is compressed and adapted to lockingly grip downwardly into the sash when the spring body portion is released.

Still another object of the invention is the provision of a spring type of window sash holder 10 consisting of a continuously curved metallic body strip having a cylindrical projection integrally formed at right angles to the inner surface at one end of the body strip to form a gripping or retaining head which is adapted to be lockingly sprung into a rope knot hole formed in the window sash or into a cylindrical opening made in the sash, said insertion of the cylindrical head into the opening being possible only when the spring body portion of the holder is compressed, 15 said locking engagement of one end of the curved body portion being accomplished by the energy exerted by the spring body portion when a distorting pressure thereon is released.

Another object of the invention is to provide 20 a simplified form of one-piece window sash holder having a curved spring body and having one end which is adapted to shiftably engage against the surface of a sash while the opposite end is formed with a flange or head adapted to be inserted into an opening in the sash when the holder is compressed and furthermore adapted to lockingly snap into engagement with the walls of the opening when pressure on the sash holder is released, 25 leaving the holder in a suspended position locked at its upper end to the sash and releasable only when the holder is again compressed to relieve the gripping action of the head portion thereof with the walls of the head receiving opening in the sash.

It is an important object of this invention to 30 provide window sash holders of simplified and inexpensive construction adapted to be used individually or in sets, said holders being of bowed continuously curved construction to co-act with a window frame member to hold the sash in a set position of adjustment in a window frame against rattling, each of said holders having one end thereof formed with a projecting portion positioned at right angles to the tangent of the curvature of the body of the holder permitting the projection to be engaged with the sash when the curved body portion of the holder is compressed and furthermore adapted to lockingly engage with the sash when the spring body portion of the holder is released, thereby permitting only one end of the holder to have moving contact with the sash when the sash is slidably moved in a window frame and when a variable pressure is applied to the holder due to the sash movement. 35 Another important object of the invention is

the provision of a simplified type of window sash holder consisting of a continuously curved body strip one end of which is bent over at right angles to the tangent of the curvature of the body strip to be snapped into locking engagement with an opening in a sash to hold the holder locked to the sash with the opposite depending end of the holder resiliently clamped against the sash and movable with respect thereto only when pressure is applied to the curved body portion of the holder. 10

Other and further important objects of this invention will be apparent from the disclosures in the specification and the accompanying drawings.

The invention (in preferred forms) is illustrated in the drawings and hereinafter more fully described. 15

In the drawings:

Figure 1 is a side elevation of an improved window sash control embodying the principles 20 of this invention.

Figure 2 is an elevational view of the holder looking toward the concave side thereof.

Figure 3 is a fragmentary elevational view of a window frame of double-hung sash construction showing improved sash holders of the type illustrated in Figures 1 and 2 mounted against side surfaces of upright members of the sashes and in sliding contact with the inner face of a window frame stile to ride in the guide grooves 30 formed by the retaining strips and the parting strip of the window frame.

Figure 4 is a fragmentary elevational view of a corner portion of a window frame illustrating an arrangement whereby the sash holders are engaged or hung from slots provided in the inner surface of an upright member of a window sash to position the holders between the sash and the inner retaining strip of the window frame.

Figure 5 is an enlarged fragmentary and sectional view of a portion of a window frame and a sash showing a flanged type sash holder locked in suspended position to a sash member and compressed to engage the sash and the window frame stile to hold the sash in a set position of adjustment in the frame against rattling. 40

Figure 6 is a fragmentary elevational view of a portion of one of the upright members of a window sash provided with a slot in which the hook or flange supporting end of a holder is lockingly engaged between the upper and lower surfaces of the slot by the released spring action of the curved body portion of the holder and showing the outer end of the hook or flange gripping into the lower wall of the slot while the upper end of the flange, where it joins the body portion, is forced against the upper surface of the slot to provide an arrangement whereby the lower free end of the holder is resiliently held in contact with the side surface of the window sash member as more clearly shown in Figure 5. 50

Figure 7 is an inner faced view of a modified form of sash holder having a toothed or serrated locking projection or flange formed at right angles to one end of the curved body portion of the holder. 60

Figure 8 is a fragmentary elevational view of a portion of a window frame sash member which may be mounted similar to the arrangement illustrated in Figures 5 and 6 when a slot is provided in a sash member but may also be used when no slot is provided by first engaging the toothed end of the hook or flange portion of the holder against the side surface of the window sash member and compressing the bowed spring 70

body portion of the holder into a substantially straight position as illustrated in this figure.

Figure 9 is a fragmentary elevational and sectional view similar to that illustrated in Figure 8 showing the second step for mounting the modified form of sash holder of the type illustrated in Figure 7 showing the toothed hook or flange end being driven straight into the sash member and with the spring body portion of the holder still compressed.

Figure 10 is a view similar to Figure 9 but showing the spring body portion of the holder released and bowed outwardly into normal position causing the toothed end of the flange to grip and slightly move downwardly into the sash member to lock one end of the holder in suspended position with the opposite end free for slidable movement on the surface of the sash member when pressure is applied to the curved spring body portion of the holder.

Figure 11 is a fragmentary elevational view of a window sash member formed with a cylindrical opening or using the opening of a window sash provided for usually receiving the rope of a weight controlled type of sash, said opening having a cylindrical holder head shown in dotted lines for insertion in the opening with the body portion of the holder shown in dotted lines and compressed, and also showing the body portion of the holder in full lines when released to cause the cylindrical head to lockingly grip against opposite surfaces of the sash opening to hold the modified form of the sash holder locked in position suspended on the sash and ready to co-act with a stile of a window frame in which the sash is mounted, similar to the arrangement as illustrated in Figure 5.

Figure 12 is a side elevational view of the second modified form of sash holder of the type illustrated in Figure 11.

In the drawings:

Referring to Figures 1 to 6 of the drawings, one improved, simple and inexpensive form of a window sash holder or control is illustrated for use individually or in sets on window sashes for co-action with members of the window frame for the purpose of holding or retaining the window sashes in set positions of adjustment within the window frame.

The window sash holder or control as clearly illustrated in Figures 1 and 2 is preferably constructed of cold rolled spring steel and affords a window sash holding means which permits of the use of a less expensive window construction wherein the ordinary sash weights, chains, cords or pulleys are not required and wherein no box frames with weight pockets are necessary. In addition to holding the window sashes in set positions of adjustment within a window frame the improved devices also serve as a means for eliminating rattling.

The form of window control or holder as shown in Figures 1 and 2 comprises a metal body portion or strip 1 of a selected width and thickness. The body portion 1 is shaped in the form of an arc and is curved continuously from one end to the other. The lower end of the metal body strip is rounded or partially tapered to form a free contact tip 2 adapted, when the window control is in position on a window sash to have movable contact with a surface of the window sash, on which the opposite or upper end of the control is lockingly secured. The upper or opposite end of the continuously curved body portion or strip 1 is deflected or bent over to form

a hook or locking flange 3 with the line of fold being transversely across the body strip and at right angles to the side edges thereof. The locking flange 3 is formed at right angles to a tangent of the curvature of the body portion 1.

The improved window retainer or control may be used individually or in sets depending upon the size of a window sash on which the device may be intended for use. In the ordinary type of window with a double-hung sash construction, a set of four window controls is used with two controls for each of the upper and lower sashes. As illustrated in Figures 3 and 4, the reference numeral 4 indicates a window frame including an upright side member, stile or jamb 5 having an inner surface 6. Secured against the inner face 6 of the jamb or stile 5 of the window frame is an inner retaining or stop strip 7, an intermediate or parting strip 8 and an outer retaining or stop strip 9. The inner stop strip 7 and the parting strip 8 on each side of the window frame provides a guide groove or channel in which the lower sash 10 is permitted to slide. The upper sash 11 is permitted to slide between the parting strip 8 and the outer retaining or stop strip 9 which form a guide channel or groove for the movement of said upper sash. The side members of the lower sash 10 are designated by the reference numeral 12 while the side members of the upper sash 11 are designated by the numeral 13.

In order to control the window sashes 10 and 11 in set positions of adjustment within the window frame the improved window sash control or spring fasteners may be secured either between one side of the sash and the window frame stile as shown in Figures 3 and 5, or the controls may be mounted between the inner faces of the side members 12 and 13 of the lower and upper sashes and respectively in back of the inner stop strip 7 and the lower sash, and between the parting strip 8 and the inner face of the side member 13 of the upper sash, as illustrated in Figure 4.

The mounting of one of the window sash controls or holders is readily accomplished by first providing a transverse saw slot 14 transversely across the outer side face 15 of the side member of a window sash. After the slot has been provided the edge of the locking flange 3 of the holder is positioned in the opening of the slot and the body portion 1 has the lower tip end 2 thereof seated against the surface 15. To secure the control in locked hanging position on the sash, pressure is applied to the curved body strip 1 to deflect the same and thereby turn the flange into a position substantially parallel to the upper and lower walls of the slot 14 permitting the flange 3 to enter the slot as shown in dotted lines in Figure 6. As the body portion of the control is compressed and the frame enters the slot 14 the pressure on the body portion 1 is released thereby permitting the same to spring outwardly and at the same time force the flange 3 to snap into a locking position within the slot 14 at an angle as clearly illustrated in Figure 6, to grip into the lower wall of the slot and press against the upper wall of the slot to thereby lock the control in suspended position on the side surface 15 of the side member of a window sash. If, as shown in Figure 3, two controls are needed for each of the sashes, the controls may be mounted in the respective slots 14 provided in the sash members. The mounting of a sash control or holder as described leaves the lower tip end 2 of the control resiliently

pressed against the surface 15 of a window sash and permits slideable movement of the tip end on said surface when pressure is applied to the curved body 1 of the control.

With the set of spring controls or holders engaged on the upper and lower window sashes in the manner described the sashes may be readily mounted in the window frame between the respective stop and parting strips with the body portions of the controls compressed as shown in Figure 5 with the outer convex surfaces of the controls in slideable contact with the inner surface 6 of a window frame stile or jamb 5. The controls or holders are thus supported on one side of the window sashes so as to resiliently hold the window sashes in position with the opposite sides of the sashes held in contact with the surface 6 of the opposite frame stile thereby holding the sashes in position against rattling in the frame and furthermore serving as a means for permitting the sashes to be moved upwardly and downwardly in the window frame and be retained in any selected open position of adjustment in which it may be desired to position the sashes.

In case it is desired to mount the sash control between the side members of the window sashes and the sash retaining or guide strips of the sashes, it may be done as illustrated in Figure 4, by providing slots 16 in the inner face of the side member 13 or 12 of the respective upper and lower sashes. With the slots 16 provided in the selected locations it is only necessary to mount the sash control by engaging the flange end 3 thereof in the opening of a slot and then compress the curved body portion until the flange 3 snaps into locking engagement within the slots, similar to the arrangement illustrated in Figure 6, when pressure on the body portion 1 of the control is released.

Attention is called to the fact that by providing the sash controls or holders with a continuous curve from one end to the other, and, having the flange 3 formed at right angles to a tangent line of the curvature of the body portion 1 of the control it is possible to snappingly lock the flange 3 in a receiving slot provided in a window sash with the outer and inner end of the flange gripping against opposite surfaces of the slot to resiliently hold the tip end 2 of the control in contact with a surface of the sash. The flange supporting end of the control is so tightly locked in the slot that it is only possible to remove the control by first compressing the spring body portion 1 of the control and then using a screw driver or other tool at the supporting end of the control to force the locking flange 3 out of a slot into which it is engaged.

Referring to Figures 7 to 10 inclusive, of the drawings, a modified form of window sash control or holder is shown. The modified control comprises a metallic spring body portion or strip 17 bowed or curved from end to end as illustrated in Figure 10. One end of the body strip 17 is tapered to provide a tip 18 adapted to resiliently and movably press against a surface of a window sash when the control is mounted on the sash. The opposite or upper end of the body strip 17 is bent over at right angles to a tangent to the curvature of the body portion 17 to form a locking and supporting flange or hook 19 the outer end of which is serrated to provide gripping teeth 20.

The tooth type of sash control may be mounted in position on a window sash similar to the

method employed in the mounting of the type of control illustrated in Figures 1 to 6. The toothed type of sash control, however, is also adapted for mounting on window sashes which are not provided with receiving slots. To mount a sash control of the tooth type on a window sash without a receiving slot, the control is placed against a surface of the sash and the body portion 17 is then compressed into a substantially straight position as illustrated in Figure 8. The toothed flange is then hammered or driven into the sash member 21 as illustrated in Figure 9. With the toothed flange engaged in position the compressed spring body portion is released permitting the spring body by resilient action to spring outwardly into the position illustrated in Figure 10 thereby causing the inserted toothed flange 19 to have a tendency to swing downwardly and grip into the material of the sash member 21 into a locking position to hold the control suspended in place ready to permit the window sash to be mounted in a window frame to permit the control to serve as a means for preventing rattling of the sash and also to permit the sash to be held or retained in a set position of adjustment within the window frame.

If desired, the toothed type of sash control may be constructed of a lighter spring steel and may be made smaller than the type of control illustrated in Figures 1 and 2. When the toothed types of sash controls are of light weight material a set of eight controls is usually provided for a window, four controls for each of the window sashes.

Figures 11 and 12 illustrate another modified form of window sash control which comprises a curved metal body strip 22 which is of concavo-convex form with the curvature extending from end to end of the body portion. One end of the body portion 22 is tapered or rounded to form a tip 23 which is the lower end of the control when the same is mounted in position and which resiliently contacts a surface of a window sash member 24 on which the control is supported. Integrally formed on one end of the concave surface of the body portion 22 and at right angles to a tangent line of the curvature of the body portion is a cylindrical locking head or support 25 which may be of solid construction or which may be hollow.

To mount the type of sash control illustrated in Figure 12 on a window sash, the sash member 24 is provided with a cylindrical recess or opening 26 or if the window sash is of the window weight control type and is already provided with the usual rope knot receiving openings, such an opening can be used for receiving the cylindrical mounting head 25 of the sash control 22.

To mount the type of sash control shown in Figure 12 it is only necessary to place the control against the surface of the sash with the free end of the locking head 25 positioned at the entrance to the opening 26. The body portion 22 of the control is then compressed from the full line position shown in Figure 11 into the dotted line position to properly position the locking head 25 so that it can be inserted into the recess or opening 26 when the head 25 is substantially axially aligned with the opening. After the head 25 has been inserted the pressure on the spring body portion 22 is released thereby causing the body portion to spring outwardly into its normal position and causing tilting of the head 25 into the full line

position shown in Figure 11 thereby causing the locking head to lockingly grip the walls of the opening 26 to thereby hold the control locked in a suspended position on the window sash with the lower tip end 23 resiliently held in contact with a surface of the sash to permit movement of said free end when pressure is applied to the spring body portion 22 of the control. The sash control of the type illustrated in Figures 11 and 12 when mounted in position is so securely held that it is only possible to remove the same by compressing the body portion and using a tool such as a screw driver to force the head out of the opening 26.

It will of course be understood that various details of construction may be varied through a wide range without departing from the principles of this invention and it is, therefore, not the purpose to limit the patent granted hereon otherwise than necessitated by the scope of the appended claims.

I claim as my invention:

1. A window sash control for engagement between a member of a window frame and a window sash having an opening therein, said sash control comprising a concavo-convex spring body strip continuously curved from end to end, and a combination supporting and locking member on one end of said body strip at right angles to the curvature of the body strip adapted only to be engaged in the sash opening when the body strip is compressed toward the sash and further adapted to lockingly spring into gripping engagement with the walls of the opening when the body strip is released and springs back into normal position to resiliently clamp the free end of the body strip against the sash.

2. A window sash control for engagement with a sash member having an opening therein, said control comprising a body strip continuously curved from end to end and including a supporting projection at one end thereof adapted only to be inserted into the opening in the sash when the body strip is compressed and further adapted to swing in said opening into locking engagement with the walls of said opening when the pressure on the body strip is released permitting movement of the body strip back into its normal curved position.

3. In a window sash control for use on a sash member having a slot therein, a resilient body strip curved in one continuous curve from end to end, and a flange on one end thereof directed inwardly from the curvature of the body strip for insertion into the slot when the body strip is compressed to cause the flange to assume a position substantially parallel to the slot, said flange adapted to move and snap into locking engagement with opposite walls of the slot when the compressed body strip is released to be lockingly suspended on the sash member.

4. A window sash control for engagement with a sash member having a cylindrical opening therein, said control comprising a body strip curved from end to end and including a cylindrical supporting projection at one end thereof adapted only to be inserted into the opening in the sash when the body strip is compressed and further adapted to swing in said opening into diagonal locking engagement with the walls of said opening when the pressure on the body strip is released permitting movement of the body strip back into its normal curved position.

LEE W. KENT.
